Assignor to Manning & Tritton
Pulsa Stove Design

Dec. 469

Jeremiah D. Green of Troy N.Y. a citizen to Alexander Morrison &
Thomas W. Webb of Troy aforesaid Letter Patent No 469 Dated July 6th 1852

The schedule referred to in these Letters Patent and making part of the same

To all whom these presents shall come:

Be it known that I Jeremiah D.

Green of Troy in the County of Rensselaer and State of New York have invented or
produced a new and original design of parlor stove which I call the "Ida" and
I do hereby declare that the following is a full and exact description of the same
reference being had to the annexed perspective drawing making a part of
this specification.

The ornamental design of my stove consists
of the arabesque scroll work (a a a) and the centre piece (b b b)
arranged on the front plate A the end plate B is ornamented with the scrolls (c c)
and the centre piece (d) surrounded with the border (e) the top C has a shell work border
(f f) and each end ornamented with the arabesque scrolls (g g) and the ornamental
circular moulding (h) in the centre, the bottom D has its border ornamented with
the scrolls (i i i) and the ornamental moulding (l l) the slide damper E is
ornamented on the front with the scroll and leaf (m) and (n) the leg F is orna-
mented with scroll (o) and leaf (p).

Having thus described my design what I
claim as new and desire to secure by Letters Patent is the ornamental design and
configuration of parlor stove the same as herein described and represented in the
annexed drawing.
